(57) **CLAIM**

The ornamental design for a medical dressing, as shown and described.

DESCRIPTION

FIG. 1 is a *top, right-side, and front* perspective [top] view of [one embodiment of] a medical dressing.

FIG. 2 is [another] a *top, right-side, and rear* perspective top view of the medical dressing of FIG. 1.

FIG. 3 is a top plan view of the medical dressing of FIG. 1.

FIG. 4 is a bottom *plan* view of the medical dressing of FIG. 1.

FIG. 5 is a [far] *left side elevation* view of the medical dressing of FIG. 1.

FIG. 6 is a [near] *right side elevation* view of the medical dressing of FIG. 1.

FIG. 7 is a *front elevation* view of the medical dressing of FIG. 1; and,

FIG. 8 is a *rear elevation* view of the medical dressing of FIG. 1.

1 Claim, 8 Drawing Sheets

Matter enclosed in heavy brackets [ ] appears in the original patent but forms no part of this reissue; matter printed in italics indicates the additions made by reissue.
